CLOTHES DRYING APPARATUS

Robert S. Briggs, Upland, Calif.

Application March 14, 1936, Serial No. 68,817

9 Claims. (Cl. 34—26)

This invention relates to clothes drying apparatus.

The general object of the invention is to provide a novel device whereby heated air is passed through the clothes while they are held in an extended position.

Another object is to provide a novel garment drying device with novel means whereby a garment regains its proper size and shape while drying.

Another object of the invention is to provide a clothes drying apparatus including a cylinder having a plurality of outlets and wherein means is provided to force air into the cylinder and wherein in each outlet is separately controlled by a valve member.

Another object of the invention is to provide a garment drying apparatus which includes means to maintain a gentle stretching tension in the garment during the entire drying process so that most of the forming of the garment takes place during the latter part of the drying.

Another object of the invention is to provide a garment drying device with novel means for engaging the lower end of a garment to pull it into position so that the garment will dry without undue shrinking.

Another object of the invention is to provide a clothes drying apparatus including a heat chamber with novel means for controlling the passage of air from the heat chamber.

Another object of the invention is to provide a clothes drying apparatus including improved means for supporting a garment while it is being dried.

Other objects and advantages will be apparent from the following description taken in connection with the accompanying drawings, wherein:

Fig. 1 is a side elevation, partly in section, showing my improved clothes drier;

Fig. 2 is an end view, partly in section and partly in elevation, showing the drier;

Fig. 3 is a fragmentary top plan view of the middle portion of my improved drier;

Fig. 4 is a fragmentary top plan view showing the front portion of my device;

Fig. 5 is a top plan view of the garment holder in an expanded position;

Fig. 6 is a fragmentary end view showing my device as used to dry a pair of trousers;

Fig. 7 is a side elevation, partly in section, showing the details of my trouser engaging mechanism;

Fig. 8 is a view taken on line 8—8 of Fig. 1 showing the garment holder in a retracted position; and

Fig. 9 is a fragmentary view taken on line 9—9 of Fig. 1 showing the air control valve.

Referring to the drawings by reference characters I have shown my invention as embodied in

a clothes drying apparatus which is indicated generally at 10. As shown the apparatus 10 includes a rectangular housing 12 which consists of a top 13, a bottom 14, and sides 15. The sides 15 are provided with apertures 16 (see Fig. 4) 5 which are adapted to be closed by closures 17 hinged to each side 15 as at 18 to swing inwardly.

Each of the closures is provided with a latch 19 which when the closures are in one position engage the side of the apertures 16 as shown in Fig. 1 and which engage the opposite closure when in the position shown in Fig. 4. The latches 19 are staggered along the edge of the closure to provide proper clearance.

The housing 12 is secured as by clamps 20, to 15 a flange 21 which includes a cylindrical collar 22 which is fixed within an elongated cylinder 23 which is provided with a pair of leg members 24. The end of the cylinder 23 remote from the housing 12 is closed by a closure member 25.

A plurality of upwardly directed cylindrical pipes 26 are mounted on the upper portion of the cylinder 23 and communicate with the interior thereof. Each of the pipes 26 has a rotatable shaft 27 extending thereacross to which a bracket member 28 is secured. Each of the brackets 28 has an air control valve 29 thereon which is disposed so that when in a horizontal position it closes the pipes 26. The shaft 27 is so disposed that as the valve 29 is rocked it enters the cylinder 23 and deflects a part of the air stream in the cylinder into the pipes. 30

One end of each rod 27 extends through a pipe 26 and through a housing 30 secured to the outside of the pipe 26. A handle 31 is secured to the end of the rods 27 and is adapted to be operated to control the position of the valve 29. Suitable clamping means such as wing nuts 32 are provided to secure the valves 29 in adjusted position.

Secured to the flange 21 I provide a spider member 32 which supports an electric motor 33. The motor 33 includes a shaft 34 which extends into the end of the cylinder 23 and on which a fan 35 is mounted. The fan is rotated by the motor 33 so as to cause air to be drawn from the cylinder 23, through the flange portion 22, into the cylinder 23 and out through the pipes 26.

In order to heat the air passing into the housing 12 I provide a heating coil 36 which is formed of suitable tubular material such as copper and includes a plurality of vertical portions 37 which are adjacent their ends joined by U-shaped bent portions 38 which are directed either sidewardly or backwardly. The coil passes through suitable fins 38' and the coil further includes an inlet 39 through which steam may be led to the coil and an outlet 40 through which the steam may be discharged.

Adjacent each of the pipes 26 I provide a

hollow standard 41 which extends diametrically through and projects above the cylinder 23 and is secured at the lower end as by a bolt 42. Intermediate its length each standard is secured to the cylinder 23 by a collar 43 and set screw 44. The portion of the standard within the cylinder 23 serves to stiffen and reinforce the latter.

The hollow standards 41 adjacent the pipes 10. A and B receive support members 45 which are held in place by suitable screws 46. These supports 45 are provided with loop portions 47 which may receive garment hangers as shown at 48 above the pipe B.

15. Surrounding each of the pipes 26 are a plurality of apertures 49 through which cords 50 pass. Each of these cords is provided at its lower end with a weight 51 which may be made of lead, and at its upper end is secured to an attaching member shown as a clothespin 52, such as are in common use for securing garments on a clothesline. These clothespins 52, disposed adjacent the pipes 26, are movable from the solid line position shown adjacent the pipe B in Fig. 1 20 to the dotted line position where they engage the lower portion of a garment G to pull the garment gently downward.

Disposed upon the pipe C I show a cap member 53 which includes a lower straight portion 30 54 which surrounds the pipe C and which also includes a truncated conical portion 55 upon which a cross bar 56 is secured. A transverse guard 57 is mounted above the bar 56 and supports a lateral guard member 58.

35. A garment holder 59 is secured to the bar 56 below the guards 57 and 58 by a pair of shafts 60. The holder 59 comprises a pair of arcuate arms 61 having lugs 62 adjacent one end thereof which are pivoted about the shafts 60. (See 40 Figs. 5 and 8.) An operating handle 63 includes a stem 64 which is slidably mounted in a tube 65 secured to the bar 56. A screw 65' is adapted to lock the stem in position.

The stem 64 is bent upwardly to form a portion 45 67 on which a cross member 68 is mounted. The ends of the cross member are pivotally connected to one end of links 69, the other ends of which are pivoted to lugs 70 which are secured to the arms 61.

50. The hollow standards 41 adjacent the pipe C receive a support member 71 which is held in place by a screw 72 and which includes a horizontal portion 73 to which a pair of downwardly depending inverted U-shaped members 74 are attached. A pair of pulleys 75 also depend from the portion 73 and support a cord 76 which passes therethrough and to one end of which a counterweight 77 is attached.

A cross piece 78 is secured intermediate the 60 ends thereof to the end of the cord 76 opposite the counterweight and is slidably positioned between the legs of the U-shaped members 74. A trouser hanger indicated generally at 79 is secured at each end of the cross piece 78. The 65 hangers 79 each includes a stem 80 the lower end of which is secured to a pivot block 81 which is apertured as at 82 to receive pins 83 on which are pivoted trouser engaging arms 84 which include pointed ends 85. (See Fig. 7.)

70. A collar 86 is slidably positioned about the rod 80 and is pivotally connected to links 87 the opposite ends of which are pivotally secured to lugs 88 integral with the arms 84. A spring 89 has its end secured to the collar 86 and the 75 block 81 to resiliently urge the collar 86 down-

ward and in turn, through the levers 87, urge the arms 84 outward. A circumferential ring 89 limits the upward movement of the collar 86 and a pair of stops 90 integral with the block 81 limit the outward and downward movement of 5 the arms 84.

In operation the fan 35 is started and air is drawn from the housing 12 through the collar 22, the cylinder 23 and is discharged through the pipes 26 which have the valves 29 open. 10

When it is desired to employ cold air the closures 17 are positioned as shown in Fig. 4 and air is drawn in through the apertures 16. When warm air is to be used the closures 17 are positioned in the apertures 16 as shown in Fig. 1 15 and the air is drawn past the heating tubes 36 and fins 38'.

A gown or other article of clothing is supported from a suitable hanger 48 and the bottom portion is engaged by the clothespin 52. 20 The hanger 48 is then elevated by extending the rod 45 until the bottom of the gown is above the pipe 26.

When it is desired to dry a pair of trousers the waist thereof is positioned about the guards 25 57 and 58, the handle 63 is pulled outwardly spreading the arms 59 until the waist is of proper size when the parts are clamped in position.

The collars 86 are then pulled along the stem 30 80 until they engage a ring 80'. The arms 86 30 are then in a retracted position and are inserted in the bottom of the trousers and are then allowed to extend under the influence of the spring 89 until the trouser is firmly held. The counterweight holds the trousers under slight 35 tension while they are drying.

From the foregoing description it will be apparent that I have invented an improved clothes 40 drying apparatus which is highly efficient in use and of economical manufacture.

Having thus described my invention I claim:

1. In a garment drying apparatus, a hollow housing, a motor, a fan adapted to be driven by said motor, a plurality of pipes extending outwardly from said housing, said housing having a plurality of apertures therein surrounding said pipes, cords passing through said apertures, said cords being weighted on the lower end thereof within said cylinder, the other end of said cords on the exterior of the housing surrounding the pipe having dress engaging members thereon. 45

2. In a garment drying apparatus, a hollow housing having a motor therein, a fan adapted to be driven by said motor, a pipe extending outwardly from said housing, a hollow standard extending through said housing, a support member slidably engaging said standard, said pipe having a cap thereon, a trouser waist engaging member disposed on said cap, said member comprising a pair of arcuate pivoted arm members, means to simultaneously move said arm members about their pivots, means to lock said members in adjusted position, a pair of trouser leg engaging members, each of said trouser leg engaging members including a body having a pair of pivoted arms thereon, means slidably engaging said body and pivotally connected to said arms to move the latter, spring means tending to urge the arms in one direction, a cross bar on which said arms are mounted, a bracket, said bracket having dependent spaced parallel arms engaging said cross member and a counterweight for said cross bar. 55

3. In a garment drying apparatus, a hollow cylinder having a housing movably secured at one 70 75

end thereof, a motor, a fan adjacent the juncture of said cylinder and said housing and adapted to be driven by said motor, a heating coil disposed at the end of said housing remote from said 5 motor, said housing having openings on the opposite sides thereof, closures for said openings, said closures being pivoted to swing inwardly and each closure being of a width equal to substantially one half the width of said housing, 10 means to hold said closures in a closed position to allow passage from said heating device to said fan, said closures being adapted to be disposed within said housing to shut off communication between said heating coil and said fan and a pipe 15 extending outwardly from said cylinder.

4. In a garment drying apparatus, a hollow cylinder having a housing movably secured at one end thereof, a motor, a fan adjacent the juncture of said cylinder and said housing and adapted 20 to be driven by said motor, a heating coil disposed at the end of said housing remote from said motor, said housing having openings on the opposite sides thereof, closures for said openings, said closures being pivoted to swing inwardly and 25 each closure being of a width equal to substantially one half the width of said housing, means to hold said closures in a closed position to allow passage from said heating device to said fan, said closures being adapted to be disposed within 30 said housing to shut off communication between said heating coil and said fan, a plurality of pipes extending outwardly from said cylinder and means to control passage of air through each of said pipes.

5. In a garment drying apparatus, a hollow cylinder, a motor, a fan adapted to be driven by said motor, a plurality of pipes extending outwardly from said cylinder, a shaft transversely disposed in each of said pipes, an air valve on 40 each of said shafts, said shafts being positioned whereby said valve when rocked has a portion thereof projecting into said cylinder to deflect air into its associated pipe, a hollow standard extending through said cylinder, a support member 45 slidably engaging said standard, one of said pipes having a cap thereon, a trouser waist engaging member disposed on said cap, said member comprising a pair of arcuate pivoted arm members, means to simultaneously move said members 50 about their pivots and means to lock said members in adjusted position, a pair of trouser leg engaging members, each of said members including a body having a pair of pivoted arms thereon, means slidably engaging said body and pivotally 55 connected to said arms to move the latter, spring means tending to urge the arms in one direction, a cross bar on which said arms are mounted, a bracket, said bracket having depending spaced parallel arms engaging said cross member and 60 a weight member engaging said cross bar.

6. In a garment drying apparatus, a hollow cylinder having a housing movably secured at one end thereof, a motor, a fan adjacent the juncture of said cylinder and said housing and adapted to 65 be driven by said motor, a heating coil disposed at the end of said housing remote from said motor, said housing having openings on the opposite sides thereof, closures for said openings, said closures being pivoted to swing inwardly and each 70 closure being of a width equal to substantially one half the width of said housing, means to hold said closures in a closed position to allow passage from said heating device to said fan, said

closures being adapted to be disposed within said housing to shut off communication between said heating coil and said fan, a plurality of pipes extending outwardly from said cylinder, an air valve for each of said pipes, a hollow standard 5 extending through said cylinder, a support member slidably engaging said standard, one of said pipes having a cap thereon, a trouser waist engaging member disposed on said cap, said member comprising a pair of arcuate pivoted arm 10 members, means to simultaneously move said members about their pivots and means to lock said members in adjusted position, a pair of trouser leg engaging members, each of said members including a body having a pair of pivoted 15 arms thereon, means slidably engaging said body and pivotally connected to said arms to move the latter, spring means tending to urge the arms in one direction, a cross bar on which said arms are mounted, a bracket, said bracket having depending spaced parallel arms engaging said cross member and a counterweight for said cross bar.

7. In a garment drying apparatus, a hollow housing having a motor therein, a fan adapted to be driven by said motor, a plurality of pipes 20 extending outwardly from said housing, a shaft in each of said pipes, an air valve on each of said shafts, said shafts being disposed whereby said valve when rocked has a portion thereof 25 projecting into said housing to deflect air into the pipe, said housing having a plurality of dress engaging members thereon surrounding each pipe, means normally urging said dress engaging members towards said housing, and means above each 30 pipe for supporting a dress.

8. In a garment drying apparatus, a hollow housing having a motor therein, a fan adapted to be driven by said motor, an outlet pipe on said housing, a support member adjustably mounted 35 on said pipe, a trouser waist engaging member disposed above said pipe, said member comprising a pair of arcuate pivoted arm members, means to move said members about their pivots, means to lock said arm members in adjusted position, a pair of trouser leg engaging members, each of 40 said trouser leg engaging members including a body having a pair of pivoted arms thereon, means slidably engaging each body and pivotally connected to said arms to move the latter, a 45 cross piece on which said bodies are mounted, means to support said cross piece on said support member, a bracket on said support member, said bracket having dependent spaced parallel arms engaging said cross piece and a counterweight for said cross piece.

9. In a garment drying apparatus, a hollow cylinder having a housing movably secured at one end thereof, a motor, a fan adjacent the juncture of said cylinder and said housing and adapted to be driven by said motor, heating means 50 in said housing, said housing having openings on the opposite sides thereof, closures for said openings, said closures being pivoted to swing inwardly and each closure being of a width equal to substantially one half the width of said housing, said closures when in a closed position allowing passage from said heating device to said fan, said closures being adapted to be disposed within said housing to shut off communication 55 between said heating means and said fan and a pipe extending outwardly from said cylinder.
